BUILDING WALL

Joseph K. Gannett, Chagrin Falls, and Robert H. Strasmyer, Lakewood, Ohio, assignors to The Austin Company, East Cleveland, Ohio, a corporation of Ohio

Application September 3, 1952, Serial No. 21,292

Term of patent 14 years

(Cl. D13—1)

To all whom it may concern:

Be it known that we, Joseph K. Gannett and Robert H. Strasmyer, citizens of the United States and residing, respectively, at Chagrin Falls, in the county of Cuyahoga and State of Ohio, and Lakewood, in the county of Cuyahoga and State of Ohio, have invented a new, original, and ornamental Design for a Building Wall, of which the following is a specification, reference being had to the accompanying drawing, forming a part thereof, in which:

Fig. 1 is a perspective view of a building wall, showing our new design;

Fig. 2 is a partial transverse section taken through said building wall on section line 2—2 of Fig. 1 and further illustrating the surface contour of a portion of the wall; and

Fig. 3 is a vertical section taken through said

building wall as indicated by section line 3—3 of Fig. 1.

We claim:

The ornamental design for a building wall, substantially as shown.

JOSEPH K. GANNETT.
ROBERT H. STRASMYER.
